UNITED STATES PATENT OFFICE.

SEPTIMA ALLSOPP, OF CLEVELAND, OHIO.

COMBINED GAITER AND OVERSHOE.

1,032,643.

Specification of Letters Patent. Patented July 16, 1912.

Application filed January 10, 1912. Serial No. 670,362.

To all whom it may concern:

Be it known that I, SEPTIMA ALLSOPP, a citizen of the United States, residing at Cleveland, in the county of Cuyahoga and State of Ohio, have invented a new and useful Combined Gaiter and Overshoe, of which the following is a specification.

My invention relates to protecting means for boots or shoes and consists in a novel and efficient combined gaiter and rubber shoe, having many features of advantage and utility as hereinafter made apparent.

Speaking in general terms my overshoe consists of a gaiter portion and a rubber shoe minus the heel, together with a fastening means or strap for securing the shank of the sole of the rubber shoe against the corresponding portion of the regular boot or shoe to which it is applied, thereby sealing the rubber shoe at that point and adjacent the heel of the regular boot or shoe, the overshoe being also sealed around the upper portion of the heel of the boot or shoe by the upper portion of the rubber shoe.

In the drawing Figure 1 is a side elevation of my combined gaiter and rubber shoe shown applied to an ordinary shoe; Fig. 2 a side elevation of the opposite side thereof; Fig. 3 a bottom plan view; Fig. 4 an elevation of my combined gaiter and shoe shown detached from the boot or shoe and Fig. 5 a detail section on the line 5-5 of Fig. 3, the same being on a somewhat larger scale.

Referring to the present embodiment of my invention as shown in the drawing my combined gaiter and shoe comprises essentially the gaiter portion 1 and rubber shoe portion 2, the former being secured at its lower edges in suitable manner to the upper edges of the rubber shoe. The gaiter portion which may be made of suitable material, preferably of a waterproof character and of any desired color, is adapted to be opened on one side but to be fastened in suitable manner as by means of the buttons.

The rubber shoe portion is substantially the same as an ordinary rubber shoe except that it has no heel but the upper portion 2^a which corresponds to the upper part of the heel portion is retained and has a side opening corresponding to the side opening in the gaiter portion 1. The rubber shoe is also provided with a flap 2^b which is an extension of the shank 2^c of its sole. This shank and flap are adapted to be held

tightly against the under portion of the boot or shoe indicated in dotted lines at 4, the shank of the rubber shoe against the corresponding portion of the boot or shoe and the flap against the breast of the heel 4^a of the boot or shoe. For the purpose of tightly securing the under portion of the shoe to the regular boot or shoe and thereby sealing the same thereat, and for also holding the overshoe upon the boot or shoe I provide suitable means which in this instance consists of a strap 5 and buckle 6 which are here shown as attached to opposite sides of the gaiter portion. This strap 70 extends below the shank 2^c and has the effect of holding such shank and the flap 2^b against the shoe for the purposes stated. By employing a strap and buckle I am enabled to cause the overshoe to fit upon any 75 size or form of shoe and yet obtain the desired sealing at the points mentioned. By preference the strap 5 is secured intermediate its length to the shank 2^c so that the end of the strap will always be projected 80 adjacent the buckle for convenient manipulation and will also draw the shank tightly against the regular boot or shoe when the strap is buckled.

The overshoe is also sealed at the upper 85 portion of the heel 4^a of the regular boot or shoe inasmuch as I retain the upper part of the heel portion 2^a of the rubber shoe so that when the gaiter is buttoned up the overshoe is effectually sealed at every point. 90

My overshoe can be very readily applied and detached and is moreover extremely light and at the same time very serviceable and absolutely water-tight. Moreover, the construction and arrangement is such that 95 it may be applied to or fitted upon any boot or shoe within reasonable limits without affecting its water-tight quality. Furthermore, the gaiter portion may be made of any desired color and may be water-proofed 100 or not, as may be desired.

I claim:

1. A combined overshoe and gaiter comprising an overshoe without a heel, a gaiter secured thereto, said overshoe having a flap 105 portion at the end of the shank portion of its sole, and means for holding such flap against the breast of the heel of the regular shoe to which the overshoe is applied.

2. A combined overshoe and gaiter comprising an overshoe without a heel, a gaiter secured thereto, said overshoe having a flap 110

portion at the end of the shank portion of its sole, and a strap and buckle device for holding such shank portion against the corresponding portion of the regular shoe and 5 for holding the flap against the breast of the heel of the latter shoe.

3. A combined overshoe and gaiter comprising an overshoe without a heel, a gaiter secured thereto, said overshoe having a flap 10 portion at the end of the shank portion of its sole, and a strap and buckle device se-

cured to the gaiter for holding such shank portion against the corresponding portion of the regular shoe and for holding the flap against the breast of the heel of the latter 15 shoe, said strap being also secured to the shank of the sole of the overshoe.

SEPTIMA ALLSOPP.
